UNITED STATES PATENT OFFICE.

CHARLES M. DEDRICK, OF TEMPERANCEVILLE, PENNSYLVANIA.

IMPROVED APPARATUS FOR REMOVING THE WIRE FROM SODA-WATER BOTTLES.

Specification forming part of Letters Patent No. **58,388**, dated October 2, 1866.

To all whom it may concern:

Be it known that I, CHARLES M. DEDRICK, of Temperanceville, in the county of Allegheny and State of Pennsylvania, have invented a new and useful Improvement in Apparatus for Removing Wire off the Corks of Soda and Mineral Water Bottles; and I do hereby declare the following to be a full and exact description thereof, reference being had to the accompanying drawings and the letters of reference marked thereon.

My invention consists in a new and improved apparatus for removing the wire off the corks of soda and mineral water bottles, said apparatus being constructed and operated in the manner hereinafter described.

To enable others skilled in the art to make and use my invention, I will proceed to describe its construction and operation.

In the accompanying drawings, Figure 1 is a perspective view of my improved apparatus attached to the lower side of a counter with a soda-water bottle inserted ready to have the wire removed. Fig. 2 is a longitudinal section of my apparatus.

In Figs. 1 and 2, A is the base or lever. C is the fulcrum; B, the catching-point, and e the screw-holes for fastening it up to the counter or other object. D is the bottle. f is the cork, and g is the wire used for holding the cork in the bottle.

In the construction of my apparatus I cast the base A, fulcrum C, and catching-point B

all in one piece, and of any suitable material, such as iron or brass, and drill two holes, e, in it to receive wood-screws, for the purpose of fastening it to the counter.

The manner in which I use my invention is as follows: Having the apparatus fastened in the desired place and position, I insert a bottle, as shown in Fig. 1, with the catching-point B against the wire g, and the neck of the bottle against the fulcrum C, and I then move the body of the bottle in the direction indicated by the arrow n, which motion will cause that part of the bottle above the point where it comes in contact with the fulcrum C to move in the direction indicated by the arrow o, thereby causing the cork f to move away from under the wire g, which completes the operation.

Having thus described the nature, construction, and operation of my improvement, what I claim as of my invention is—

The apparatus consisting of the base or lever A, fulcrum C, and catching-point B, when said apparatus is used for the purpose of removing wire off the corks of soda or mineral water bottles, the whole being constructed, arranged, and operating substantially as herein described and set forth.

CHARLES M. DEDRICK.
